F. S. McCULLOUGH

THERMIONIC TUBE CONSTRUCTION

Filed June 2, 1924

INVENTOR
Frederick S. McCullough
by C. M. Clarke
attorney

UNITED STATES PATENT OFFICE.

FREDERICK S. McCULLOUGH, OF WILKINSBURG, PENNSYLVANIA.

THERMIONIC-TUBE CONSTRUCTION.

Application filed June 2, 1924. Serial No. 717,232.

To all whom it may concern:

Be it known that I, FREDERICK S. McCULLOUGH, a citizen of the United States, residing at Wilkinsburg, in the county of Allegheny and State of Pennsylvania, have invented certain new and useful Improvements in Thermionic-Tube Constructions, of which the following is a specification.

This invention is for a thermionic tube construction wherein one or more coils are enclosed within the walls of the tube, as outlined in my co-pending application Serial No. 308,978, filed July 7, 1919, and which will be issued as a patent on June 3, 1924.

In my said application, it is proposed to include coils of a thermionic tube circuit within the envelope of the tube, whereby a number of external lead connections may be eliminated and a material advantage result in the shortening of lead wires and the consequent reduction of distortion due to the decreased impedance and capacity of such leads. Such a construction, furthermore, enables apparatus involving the use of thermionic tubes to be very compact by reason of the saving of space gained by the elimination of such coils and lead wires.

The present invention has for its object to provide a novel supporting means for coils within a tube.

A further object of the invention is to provide a novel transformer construction within a thermionic tube.

These and other objects and advantages are obtained by my invention, which may be understood by reference to the accompanying drawings, in which:

Fig. 1 is a somewhat diagrammatic front elevation of a device embodying my invention;

Fig. 2 is a side view thereof;

Fig. 3 is a section in the plane of line III—III of Fig. 2;

Fig. 4 is a wiring diagram illustrating a circuit embodying tubes of my invention;

Fig. 5 is a diagrammatic view of wiring of one type of tube embodying the invention;

Fig. 6 is a front view of a slightly modified form; and

Fig. 7 is a view showing a different circuit connection embodying my invention.

In the drawings, 5 designates the usual glass stem of a thermionic tube construction which is flanged at 6, the flange being se-

cured to the envelope 7 (shown in dotted lines) after all the parts have been assembled in accordance with the usual practice.

Carried by the stem are two spaced apart rigid supports 8 which carry the plate 9 of the tube. The upper ends of the posts 8 project above the top of the plate a considerable distance, passing through opposite ends of a heat resistant insulating cylinder or body 10, which is thus rigidly supported above the plate.

Carried on or supported by this cylinder are one or more coils for use in the thermionic tube circuit. I have shown two such coils, 11 and 12, the former being included in the plate circuit of the tube as the primary of a radio-frequency transformer, while the latter, designated 12, constitutes the secondary winding of the transformer.

The remaining portion of the tube may follow any standard or preferred construction. I have shown a filament or hot cathode 13 carried by supports 14 and 15 in the stem. The grid 16 is carried by supports 17 and 18, also fused into the stem. The three electrodes may connect with the usual connector plugs at the base of the tube.

In Figs. 1 and 5, 19 designates the two filament connections, 20 is the grid connection, and 21 is the plate terminal.

In the form illustrated, the coil 11 is in series with the plate, while coil 12 has one terminal connected in the filament circuit inside the tube, its other end passing through the glass envelope of the tube, as indicated at 22, the projecting wire 23 being adapted for connection with other parts of the circuit. I have shown it, in Fig. 4, as leading to the grid of similar tube.

In Fig. 4, which illustrates a circuit possible with my invention, two tubes A and B are coupled together for effecting radio frequency amplifications in a radio-receiving system.

Various other circuits and connections for the coils may be devised for utilizing the principles of my invention, and will readily suggest themselves to those familiar with thermionic or electron valve circuits.

In Fig. 6, I have shown a slight modification wherein the stem 25 has supports 26 which carry the plate 27. Within the plate are the usual filament 28 and grid 29. Carried on the plate supports is a heat resistant cylinder or tube 30 that surrounds the elec-

- trodes, on which are carried one or more coils, such as 31 and 32, which may be connected in the circuit as hereinbefore described, or in any other suitable fashion.
- 5 One coil, for instance, might be included in the grid circuit of the tube and the other in the plate circuit, to effect regeneration. This is suggested in the wiring diagram outlined in Fig. 7.
- 10 Various other changes and modifications may be made in the construction of the tube and in the circuit connections within the contemplation of my invention and under the scope of the appended claims.
- 15 What I claim is:
1. An electron tube having hot and cold electrodes therein, a coil supporting member inside the tube, and inductively coupled coils on the supporting member.
  2. An electron tube comprising an envelope having an anode, a cathode and a grid therein, a coil supporting member inside the vessel, inductively coupled coils on the supporting member, one of said coils
- being connected inside the tube with one of the electrodes.
3. An electron tube comprising an envelope having an anode, a cathode and a grid therein, a coil supporting member inside the vessel, inductively coupled coils on the supporting member, one of said coils being in series with the anode of the tube.
4. A thermionic tube comprising an envelope, a stem within the envelope, three electrodes comprising a grid, a plate, and a cathode, respectively, inside the tube, supporting means inside the tube for the grid and cathode, supporting means in the tube for the plate, a heat resistant insulating body carried by the plate, supporting means in spaced relation thereto, a pair of inductively coupled coils carried by the body, each coil having an internal connection with one of the electrodes.
- In testimony whereof I hereunto affix my signature.

FREDERICK S. McCULLOUGH.
